UNITED STATES PATENT OFFICE.

CYRUS L. ADLER, OF LOUISVILLE, KENTUCKY.

DESIGN FOR A RADIO CONSOLE CABINET.

Application filed April 29, 1925. Serial No. 13,257. Term of patent 3½ years.

To all whom it may concern:

Be it known that I, CYRUS L. ADLER, a citizen of the United States, residing at Louisville, in the county of Jefferson and State of Kentucky, have invented a new, original, and ornamental Design for a Radio Console Cabinet, of which the following is a specification, reference being had to the accompanying drawing, forming part thereof.

The figure is a perspective view of a radio console cabinet showing my new design.

I claim:

The ornamental design for a radio console cabinet, substantially as shown.

CYRUS L. ADLER.
